Primary Examiner — Eliza Z Bennett-Hattan(74) Attorney, Agent, or Firm — Dunlap Bennett & Ludwig PLLC(57) CLAIM

The ornamental design for a keepsake display, as shown and described.

DESCRIPTION

FIG. 1 is a front perspective view of a keepsake display; FIG. 2 is a front elevation view thereof; FIG. 3 is a rear elevation view thereof; FIG. 4 is a left elevation view thereof; FIG. 5 is a right elevation view thereof; FIG. 6 is a top plan view thereof; and, FIG. 7 is a bottom plan view thereof. The broken lines shown in the drawings illustrate portions of the keepsake display that form no part of the claimed design. The keepsake display is shown with a symbolic break in its length. The appearance of any portion of the article between the break lines forms no part of the claimed design.

1 Claim, 3 Drawing Sheets(56)
